UNITED STATES PATENT OFFICE.

HERMAN WEBER, OF CHICAGO, ILLINOIS.

DUMPING PAN FOR LAUNDRY MACHINES.

Application filed January 7, 1921. Serial No. 435,592.

To all whom it may concern:

Be it known that I, HERMAN WEBER, a citizen of the United States, and a resident of the city of Chicago, county of Cook, and

State of Illinois, have invented certain new and useful Improvements in Dumping Pans for Laundry Machines, of which the following is a specification.

My invention relates to dumping pans for laundry machines and it has for its principal object the provision of a new and improved arrangement of parts by which a predetermined amount of water may be readily measured out and held in readiness for use for the succeeding operation of the machine to which the device is applied, whereby such accurately measured charge of water can be fed quickly and easily to the machine.

Other objects will appear hereinafter.

The invention consists in the combinations and arrangements of parts hereinafter described and claimed.

The invention will be best understood by reference to the accompanying drawings forming a part of this specification, and in which,

Fig. 1 is a view of my improved apparatus as applied to a washing machine;

Fig. 2 is a vertical cross section, through my improved apparatus, being taken substantially on line 2-2 of Fig. 1;

Fig. 3 is a fragmentary view, being a vertical section taken through my improved dumping pan structure at one side thereof;

Fig. 4 is a cross section taken on line 4-4 of Fig. 3;

Fig. 5 is a cross section similar to Fig. 4 but showing the condition of the valve when the pan is turned into dumping position;

Fig. 6 is a face view of one of the rack bars by which the position of the pan is controlled; and

Fig. 7 is an edge view of the parts shown in Fig. 6 as seen from the left in that figure.

Referring to the several figures of the drawings, 10 indicates the body of a washing machine of any approved type, supported by standards 11 at its ends. An

open-ended tank 12 is mounted at one side of the machine 10 in position to extend a short distance above the machine, being supported in position by any suitable means. The tank 12 is open at its lower end portion,

being in communication with the interior of the body of the washing machine through-

out the full length of the tank, as is indicated by dotted lines in Fig. 1, the arrangement being such that the tank is adapted to be emptied in a very short time when a quantity of water is placed therein.

Within the tank 12, and adjustable vertically with respect thereto, I have provided a receptacle or pan 13, which also is open along its top portion. For the purpose of providing that the pan 13 may be emptied very quickly into the tank 12, I have mounted the pan revolubly in position so as to be turned in clockwise direction in Fig. 1. For providing means for feeding water to the pan 13 in its various adjusted positions vertically, and for taking care of the vertical movement of the pan with respect to the tank 12 and for the pivotal movement of the pan about its longitudinal axis, I have provided pivotal mounting means comprising a sleeve 14 fixedly mounted upon the pan 13 at one end, such pivotal mounting means being revolubly mounted within slide blocks 15 which are movable vertically in slots 16 provided in the end of the tank 12. In the construction shown, the pivotal mounting member at the end of the pan opposite that at which the sleeve 14 is mounted, is also in the form of a sleeve which is indicated by 17, the inner end of the sleeve 17 being closed by a plug 18 of any suitable type. Handles 19 of any approved form are fixedly mounted upon the outer ends of the sleeves 14 and 17 for turning the pan 13 about its pivotal axis within the tank 12.

For controlling the position of the slide blocks 15, I have provided rack bars 20 which in the construction shown are formed integrally with the slide blocks. A longitudinally extending shaft 21 is journaled in the ends of the tank 12, being provided with segmental gears 22 upon its ends, meshing with the rack bars 20. The shaft 21 is provided with a handle 23 fixedly mounted thereon at one end for turning the shaft 21 for effecting a vertical movement of the rack bars 20 with the slide blocks 15 and the pan 13 carried thereby. For holding the pan 13 in the desired elevated position, I have provided a pawl 24 pivotally mounted upon a bracket 25 carried by the end of the tank 12, such pawl being adapted by engagement with a segmental ratchet 26 to prevent rotation of the shaft 21 in clockwise direction in Fig. 1, serving thus to prevent downward movement of the pan 13 within the tank.

For delivering water to the pan 13, I have provided a pipe 27 extending into and through the sleeve 14 into position within the pan 13, the end of the sleeve 14 about 5 the inner end of the pipe 27 being enclosed by means of a cap 28. The pipe 27 is designed to have a close working fit within the sleeve 14 and the cap 28 so as to normally prevent the escape of water between 10 such parts, communication being provided between the pipe 27 and the interior of the pan 13 by means of ports 29 and 30 in the walls of the pipe 27 and the cap 28, as is best shown in Fig. 4, such ports being in registering position when the pan 13 is in its normal upright position. When the pan 13 is turned 15 in clockwise direction in Fig. 1 for dumping the contents of the pan into the tank 12, the port 30 is turned out of registry with the port 29 into approximately the position shown in Fig. 5, whereby the delivery of water through the pipe 27 to the pan 13 is prevented, this result being attained automatically upon the operation of giving the 20 pan 13 an operative rocking movement for dumping its contents. As is indicated by dotted lines in Fig. 2, the inner end of the pipe 27 is preferably closed by the plug 31.

The means provided for delivering water 30 to the tank 13 through the pipe 27 comprises two short pieces of pipe 32 and 33 which have a rotatable connection with the pipe 27 and with the pipe 34 respectively, the pipe sections 32 and 33 being also pivotally connected together, this construction being provided for the vertical movement of the pipe 27 with the pan 13.

Water is fed under pressure to the pipe 34 by means of pipes 35 and 36 leading from 40 tanks 37 and 38 respectively supported in position opposite the tank 12, valves 39 of any approved type being interposed in the pipes 35 and 36 for controlling the admission of water therethrough. The tanks 37 and 45 38 are designed to contain hot water and cold water respectively, being fed through pipes 40 provided with valves 41 which are controlled by balls 42 of any approved type for maintaining the level of water in the tanks 37 and 38 at the desired height. Overflow pipes 43 are provided for taking care 50 of any possible excess of water within the tanks.

As is clearly shown in Fig. 1, the tanks 37 55 and 38 are positioned with respect to the tank 12 so that the level of the water as controlled by the float valves 41 is maintained at a point corresponding substantially to the position of the sleeve 14 when moved 60 to the limit of its upward movement as is shown in Fig. 1. By this arrangement, as is indicated by the dotted line representing the level of the water in said figure, when the valves 39 are opened, the water will be 65 of comparatively small depth in the pan 13

when the pan is in its uppermost position, and will be of correspondingly greater depth when the pan is lowered through the medium of the handle 23 and its co-operating parts. With the valves 39 opened more or less completely so as to give the desired ratio of flow 70 through the pipes 35 and 36, the temperature of the water passing into the tank 13 is readily controlled. By the regulation of the vertical position of the pan 13, the 75 amount of water within the pan at any given time is very easily controlled.

By the use of my improved construction, the quantity of water of the desired temperature and of the predetermined desired 80 amount is maintained at hand adjacent to the machine 10 ready for prompt and speedy delivery to the machine 10. In operation, the operator will set the handle 23 at the desired point for placing the pan 13 in position for receiving the amount of water which will be required for the next succeeding 85 operation of the machine. Even though comparatively small pipes be provided between the tanks 37 and 38 and the pan 13, 90 the desired amount of properly tempered water is assured ready for use at the desired moment, inasmuch as the pan 13 is adapted to fill slowly during one washing operation for use during the next operation. By providing for an accurate measuring of the 95 water for use in the machine, a very great saving is effected in the amount of soap required. As will be readily appreciated, soap must be added to bring about the 100 desired condition of the water, even though an excess of the water be used, and by the use of my improved apparatus by which the 105 amount of water is very readily and easily measured and controlled, a saving of soap and fuel is very easily effected.

While I have illustrated and described the preferred form of construction for carrying my invention into effect, this is capable of variation and modification without departing 110 from the spirit of the invention. I, therefore, do not wish to be limited to the precise details of construction set forth, but desire to avail myself of such variations and modifications as come within the scope of the 115 appended claims.

Having described my invention, what I claim as new and desire to secure by Letters Patent is:

1. In combination, a tank; a receptacle 120 adjustably mounted on said tank and being adapted to empty thereinto; means for adjusting said receptacle in said tank; means for containing and delivering water to said receptacle, said containing means being positioned to automatically limit the depth of water delivered to said receptacle, and the amount of said water depending upon the adjusted position of said receptacle; and means operable by the emptying of said 125 130

water from said receptacle for cutting off the flow of water thereto.

2. In combination, a tank open at its lower portion, a sleeve extending into said tank, a pan pivotally mounted on said sleeve as an axis, means for adjustably mounting said sleeve, and means for delivering water to said pan through said sleeve.

10 3. In combination, a tank open at its lower portion, a sleeve extending into said tank, a pan fixedly mounted on said sleeve and adapted to rock therewith, means for adjustably mounting said sleeve, means for delivering water to said pan through said sleeve, and means for turning said sleeve for dumping the water from said pan.

4. In combination, a tank open at its lower portion, a sleeve extending into said tank, a pan fixedly mounted on said sleeve and adapted to rock therewith, means for adjustably mounting said sleeve, means for delivering water to said pan through said sleeve, and means for preventing the flow of water into said pan when the pan is turned out of its normal upright position.

5. In combination, a tank open at its lower portion, a sleeve extending into said tank, a pan fixedly mounted on said sleeve and adapted to rock therewith, means for adjustably mounting said sleeve, means for delivering water to said pan through said sleeve, and valve means adapted automatically to shut off communication through said sleeve when said pan is turned for dumping the water therefrom.

6. In combination, a receptacle adapted to be emptied quickly; means for mounting said receptacle for vertical adjustment; fluid containing means mounted adjacent said receptacle; and fluid conducting means connecting said fluid containing means with said receptacle and being arranged to permit adjustment of said receptacle with respect to said containing means.

7. A device of the class described comprising in combination, a tank, a receptacle pivotally and adjustably mounted in said tank for delivering its contents thereto; means for delivering fluid to said receptacle; means for adjusting said receptacle in said tank to regulate the fluid contents of said receptacle; and means for

retaining said receptacle in adjusted position.

55

8. In combination, a receptacle adjustable vertically and adapted to be emptied quickly, a container and means for delivering water therefrom to said receptacle, means for controlling the vertical adjustment of said receptacle for regulating the amount of water deliverable thereto, and means for preventing the delivery of water to said receptacle during the operation of emptying the water therefrom.

60

9. In combination, a receptacle adjustable vertically and revoluble about a horizontal axis, a tank adjacent thereto, means for delivering water to a predetermined level in said tank, connections between said tank and said receptacle for filling the receptacle to the same level, and means for adjusting said receptacle vertically for controlling the amount of water delivered thereto.

70

10. In combination, a receptacle adjustable vertically and revoluble about a horizontal axis, a plurality of tanks adjacent thereto each adapted to contain water, means for regulating the depth of water in said tanks, connections between said tanks and said receptacle for filling the receptacle to the same level, and means for adjusting said receptacle vertically for controlling the amount of water delivered thereto.

75

11. In combination, a receptacle adjustable vertically and revoluble about a horizontal axis, a tank adjacent thereto, means for delivering water to a predetermined level in said tank, connections between said tank and said receptacle for filling the receptacle to the same level, means for adjusting said receptacle vertically for controlling the amount of water delivered thereto, and means for shutting off the flow of water to said receptacle when the receptacle is turned about its pivotal axis for dumping the water therefrom.

80

In testimony whereof I have signed my name to this specification in the presence of two subscribing witnesses.
